PAIR OF SUNGLASSES

Egon F. Von Seekamm, New York, N.Y., assignor, by
mesne assignments, to The Electric Storage Battery
Company, Philadelphia, Pa., a corporation of New
Jersey

Application February 21, 1957, Serial No. 44,938

Term of patent 14 years

(Cl. D57—1)

Figure 1 is a front elevational view of a pair of sunglasses, showing my new design.

Figure 2 is a top view thereof.

Figure 3 is a side elevational view thereof.

Figure 4 is a cross-sectional view taken along line IV-IV of Figure 1.

The characteristic features of my design for the pair of sunglasses disclosed reside in the temples having the configurations shown.

I claim:

The ornamental design for a pair of sunglasses, substantially as shown and described.
